UNITED STATES PATENT OFFICE.

ROBERT D. WEBB, OF PHILADELPHIA, PENNSYLVANIA.

DESIGN FOR A CAN-OPENER BLADE.

SPECIFICATION forming part of Design No. 27,296, dated July 6, 1897.

Application filed May 28, 1897. Serial No. 638,636. Term of patent 7 years.

To all whom it may concern:

Be it known that I, ROBERT D. WEBB, a citizen of the United States, residing in the city and county of Philadelphia, State of Pennsylvania, have invented and produced a new and original Design for the Blade of a Can-Opener, of which the following is a specification, reference being had to the accompanying drawings, forming part thereof.

5 The leading feature of my design for the blade of a can-opener is a blade of elliptical form in side elevation, terminating in a point at bottom, and convex sides terminating in sharp edges and reducing in convexity to said 10 point.

15 Figure 1 represents a side elevation of a blade for a can-opener embodying my design.

Fig. 2 represents an end elevation thereof. Fig. 3 represents a section thereof on line *xx*, Fig. 1.

In the drawings, A designates the blade of a can-opener, the same being of elliptical form in the direction of top to bottom, it being connected at top with the head B and having a point C at bottom. The sides D D are convex, terminating in the sharp edges E and reducing to said point C.

What I claim is—

The design for the blade of a can-opener, substantially as described and shown.

ROBERT D. WEBB.
